UNITED STATES PATENT OFFICE.

WILHELM OESTERREICH, OF BERLIN, GERMANY.

TELEPHONE SYSTEM.

SPECIFICATION forming part of Letters Patent No. 530,598, dated December 11, 1894.

Application filed October 12, 1893. Serial No. 487,928. (No model.)

To all whom it may concern:

Be it known that I, WILHELM OESTERREICH, electrical engineer, a subject of the German Emperor, residing at Berlin, in the Kingdom of Prussia and German Empire, have invented certain new and useful Improvements in Telephone Systems; and I do hereby declare the following to be a full, clear, and exact description of the invention, such as will enable others skilled in the art to which it appertains to make and use the same.

The present invention relates to improvements in telephone systems and is especially applicable to those plants in which in removing the telephone from the switch an electric battery is put into the circuit connecting the said telephone with the earth. The essential feature of my invention consists in the combination with a multiple switch-board of a primary or secondary pile or battery which for the purpose of testing the wires is connected with a circuit opposite to that of the telephone station in question by a circuit-closer. If in combination with the pile or battery mentioned an electric indicator, telephone or other means for ascertaining the presence of an electric current is employed, I may see from the movements of the index of such galvanometer, from the noise of the telephone or from any other suitable apparatus, whether a line is in use or not.

A special feature of my invention consists in combining with the switch lever, which serves to put the galvanometer or similar apparatus in or out of circuit, the handle of a Morse telegraph in such a manner as to enable the transmission of ordinary telegraphic dispatches through the line to be made.

In the annexed drawings my invention is represented, Figure 1 showing part of a telephone-plant and illustrating the electrical connection of the several wires and apparatus, an electric-indicator being used for indicating the electric current. In Fig. 2 a modification is represented in which instead of the electric-indicator a telephone is used. Figs. 3, 4, 5 and 6 illustrate in a plan and in vertical sections, respectively, the switch for setting the controlling device at work.

In the telephone plant represented in Fig. 1 the connection is effected in usual manner by a crank-switch U with levers f f' which alternately may be brought into contact with contact-pieces t² and t⁴ respectively and with

t' and t³. As will be seen from Fig. 1 in the first instance the speaking apparatus, in the second instance the clearing out annunciator S K is inserted. The speaking apparatus consists of the speaking-key D with parts 1, 2, and 3, the first of which is connected with the contact-piece t⁴, while the second part, 2, is connected with contact-piece t³ and also with one half of a condenser C, the other half of which is connected with the speaking apparatus of the person actuating and testing the plant. This latter speaking apparatus consists of the transmitter M, battery M B, induction-coil J R, and receiver T.

The speaking key D is used by the office to call the person who is to be spoken to, if this has not been done by the person who wishes to speak. The person in the office, for this purpose, presses the speaking key D, thus putting the speaking battery W B into circuit and permitting the current of the battery W B to go over the lever f' and the wire s' into the circuit that is to be employed.

The third part, 3, is connected with the battery W B and with earth, and also with the aforesaid speaking apparatus. The use of the key D is to connect the part 1 with the parts 2 or 3 as required. The switch U is provided with an additional switch D', which consists of the elements f² t⁵ and t⁶ of an ordinary Morse transmitter. The contact t⁵ for working position is connected with the sensitive galvanometer G and is then led to earth at E. The contact t⁶ for the position of rest is connected with the zinc pole of a copper-zinc pile C B', the copper-pole of which is likewise connected with the earth at E.

The lever f of the switch is connected by the flexible leading-wire s² with the contact-pin S². The head of this pin is made of insulating material, so that when the pin is introduced into the contact-hole the contact-spring S P is lifted from the tube a and the circuit broken. (See Fig. 1.) The lever f' is connected by the flexible leading-wire s' with the part h of the contact pin S' and lever f' is connected by the flexible leading-wire s with the point k of the same contact-pin. The head of the said contact-pin is insulated from the rear part by a disk n, and the wire s is connected with the said head, while the wire s' is connected with the rear part of the contact-pin. In introducing this pin into the contact-hole it may be seen that at first the connection with the

wire s is established, while when the pin is fully introduced the contact-spring b is removed from contact-tube a , its V shaped part resting upon the head of the pin, whereas the rear part of the pin is in connection with the tube a .

If it is desirable to know whether a certain line is at a given time in use or not, the respective tube a is touched with the point of the contact-pin S' and the key f^2 of the additional switch D' is depressed, so that it comes in contact with t^6 , as shown at the right hand in Fig. 4. The electric indicator G is thus connected by $t^6 f^2 s S' K$ with the earth, which is indicated E in all figures. The electric indicator is thus actuated in case the line tested is in use.

Figs. 4, 5 and 6 are respectively sections on the lines $a-b$, $c-d$, and e^0-f^0 , in Fig. 3, and each figure shows the lever f^2 in two positions, clearly illustrating how the various contacts are made. Fig. 3 also illustrates how the handle H is moved and shows it in two positions. When the lever f^2 is at rest it is in contact with t^6 as shown at the left hand in Fig. 4, and when used for testing it is bent backward so as to come in contact with t^5 as shown at the right hand in Fig. 4. The lever f^2 is insulated at that part which bears against the springs f' and f .

The current of the testing battery is a weak current, and it is too weak to throw down the annunciator of any line to which it may be connected, but it is strong enough to actuate the galvanometer which is very sensitive.

The current may come from the following different sources: first from the battery $C B$ of the telephone station $L B$. When the telephone of the station is removed from the contact-hook the current of the element $C B$ passes through the contact-tube a at switch-board $T B$ then to the point k of the contact-pin S^2 and through wire s , and finally through $f^2 t^5$ and through the electric indicator G to the earth; second, from another battery similar to battery $C B$, located at another station $L B'$ to the right of $C B$, and connected to the switch-board at $II B$ (or $III B$) provided the point k of the pin S' has been inserted at the respective station into the similar contact-tube a . The current issuing from this station passes for instance from contact $II B$ to contact IB and in the same way to the electric indicator G and finally to the earth as before described. If in one or more stations to the left and to the right the telephones are removed the elements $C B$ of all these stations are put in parallel with respect to the electric indicator G and will actuate the same. From this there results that the leading wires when in use are always in connection with a weak source of electricity from the station which enables an exact test of the wire to be made. The test current passes through the wire even from the moment when the telephone at the respective station is taken from the contact hook. For

the purpose of testing, the rings need only be touched with the point of the contact-pin S' . In Fig. 1 of the annexed drawings a position is shown in which the current of the test battery $C B'$ at the central office passes through t^6, f^2 , &c., to the test ring a of the switchboard IB and from here to LB , on the one hand, and to the annunciator K' , on the other. In testing such a wire it would be found that it was in use. If, however, the contact-pin S' is wholly inserted, the wire receives the current of the test battery from the station $L B$, at the left hand in Fig. 1, before the telephone has been removed from the hook, the said station being connected by contact-pin S^2 with the line wire. The current passes through $S^2 a s^2 f$ and then either through $t^6 S K t^5$ or through $t^6 2 1 t^4$ to $f' s' S' h a$ and finally to LB . Those parts of the wire situated to the right are provided with current from $C B'$.

The usual employment of the switch U for switching the flexible leading-wires either to the speaking apparatus or to the clearing-out apparatus is illustrated in Figs. 3, 4, 5 and 6. The lever f^2 is turned to the left, so as to connect f with t^2 and f' with t^4 . The speaking apparatus is thereby inserted. The peculiarity of this device is that lever f^2 is made elastic and serves as a key of an ordinary Morse transmitter. In the right hand position of this, lever f^2 is connected with t^6 —that is to say the testing battery $C B'$, is in connection with s and with the point of the contact-pin. If now the wire is to be tested the button is turned to the side, so that the lever f^2 is removed from t^6 and pressed against t^5 . $C B'$ is thereby cut out and G inserted into the circuit.

The arrangement of the several lines and apparatus inserted into them is exactly the same if instead of the electric indicator shown in Fig. 1 an acoustic or electro-acoustic indicator, such as a telephone is used. See Fig. 2.

What I claim is—

The combination, with a telephone system provided with a multiple switch board; of a testing wire connected with the earth, and provided with a weak battery, a galvanometer in a branch wire, and a contact for connecting it with the circuit to be tested; and a switch provided with a depressible and oscillatory lever f^2 , operating when depressed to leave the contact t^6 and touch the contact t^5 , and operating when moved to one side to move the springs f and f' clear of the contacts t^2 and t^4 and place them in contact with the contacts t^6 and t^5 , respectively, substantially as and for the purpose set forth.

In testimony whereof I affix my signature in presence of two witnesses.

WILHELM OESTERREICH.
